J. HOWARD.
COMMUNION SERVICE CABINET.
APPLICATION FILED FEB. 10, 1917.

Patented June 4, 1918.

UNITED STATES PATENT OFFICE.

JEWELL HOWARD, OF STRATFORD, TEXAS.

COMMUNION-SERVICE CABINET.

1,268,120.

Specification of Letters Patent. Patented June 4, 1918.

Application filed February 10, 1917. Serial No. 147,919.

To all whom it may concern:

Be it known that I, JEWELL HOWARD, a citizen of the United States, residing at Stratford, in the county of Sherman and State of Texas, have invented certain new and useful Improvements in Communion-Service Cabinets; and I do hereby declare the following to be a full, clear, and exact description of the invention, such as will enable others skilled in the art to which it appertains to make and use the same.

This invention relates to a communion service cabinet, and has for its primary object to produce a cabinet of this character by which a communion service may be quickly and noiselessly served simultaneously to all of the communicants.

With this object in view, my invention consists in the improved construction, arrangement, and combination of parts herein-
after fully described, and afterward specifically claimed.

In order that the construction and operation thereof may be readily comprehended, I have illustrated an approved embodiment of my invention in the accompanying drawings, and will now proceed to fully describe the same, having reference to said drawings, in which—

Figure 1 represents a perspective view of a cabinet constructed in accordance with my invention;

Fig. 2, a vertical, longitudinal, sectional view on the plane indicated by the broken line 2—2 of Fig. 3;

Fig. 3, a vertical, transverse, sectional view on the plane indicated by the broken line 3—3 of Fig. 2; and

Fig. 4, an enlarged, fragmentary, sectional view on the plane of Fig. 3.

Similar characters of reference are used to denote like parts throughout the accompanying drawings and the following description.

Referring more particularly to the drawings, it will be seen that my novel construction of communion service cabinet consists of a back wall 1 and a front wall 2, which is of a height less than the back wall and is connected thereto by end walls 3. The back wall 1 is designed to be attached to the back of a pew 4 by suitable fastening means such as screws or the like 5.

As shown the communion box is of rectangular construction, in this instance, and is provided with a suitable cover 6 that is hingedly connected to the rear wall 1 as indicated by the numeral 7. The cover 6 is hinged to the rear wall at a point slightly above the front wall so that when it is arranged in closed position, it will lie at an inclination to the front and back walls. In order that the cover may be closed noiselessly a strip of felt 8 is attached to the under circumferential edge of the cover and is designed to engage the upper edges of the front and end walls 2 and 3 respectively.

In order that the cover may be held and maintained either in a closed or raised position, I provide a resilient leaf spring 9 that is attached to the back wall 1 and is designed to engage cut away or flattened portions 10 at the inner edge of the cover, the rear wall being cut away as at 11 to permit the leaf spring to yield rearwardly in raising or lowering the cover. The communion box is provided with a horizontally disposed shelf 12 which is provided with a series of openings adjacent its rear edge in which are removably positioned wine glasses 13, this shelf being further provided with a series of indentations 14 adjacent its forward edge and arranged in transverse alinement with the wine glasses 13, and are each designed to contain a loaf of bread.

As clearly shown in Figs. 1 and 2 of the drawings, the front and back walls are continued beyond the opposite ends 3 and are connected at each end by an end wall 15 to provide a pocket 16 designed to contain offertory envelops. The pocket 16 is closed at its lower end by a bottom wall 17.

From the foregoing it will be apparent that with the use of communion services of this character attached to the back of the pews and arranged throughout the church, that a communion service can be given simultaneously, quickly and noiselessly to all of the communicants, pockets being provided at each end of each service whereby the communicants can deposit the envelops containing their offerings.

What I claim is:

As a new article of manufacture, a communion service cabinet comprising a box, a shelf disposed horizontally within said box

and formed adjacent to its rear wall with a series of openings to receive wine glasses, said shelf being also provided with a series of indentations corresponding in number 5 with the wine glass openings and in positions in front thereof, and a cover for said box.

Copies of this patent may be obtained for five cents each, by addressing the "Commissioner of Patents, Washington, D. C."

In testimony whereof I have signed my name to this specification in the presence of two subscribing witnesses.

JEWELL HOWARD.

Witnesses:

ROYAL PENDLETON,

JOHN HEUSER.
